UNITED STATES PATENT OFFICE.

HERBERT C. STOCKWELL, OF STAMFORD, CONNECTICUT, ASSIGNOR TO THE
YALE & TOWNE MANUFACTURING COMPANY, OF SAME PLACE.

TIME-LOCK.

SPECIFICATION forming part of Letters Patent No. 280,260, dated June 26, 1883.

Application filed March 2, 1883. (No model.)

To all whom it may concern:

Be it known that I, HERBERT C. STOCKWELL, of Stamford, in the county of Fairfield and State of Connecticut, have invented certain new and useful Improvements in Time-Locks for Safes and Vaults, &c., of which the following is a specification.

A late mode of attacking time-locks is by discharging a charge of dynamite or other quick explosive on the outside of the door to which the lock is applied, in close proximity to the lock. By this method it is possible sometimes either to break or displace one of the escapement-wheels of the time mechanism, and thus cause the time mechanism to run down and unlock the lock, or else to blow the lock off from the door altogether.

My invention is designed especially to prevent unlocking from the running down of the time mechanism caused by such explosions; and it consists in placing a pin through the back of the lock, so that it will extend across the intervening space between the lock and the door and abut against the inside of the door, or come very close to it, in such a position that if the pin is driven inward by an explosion on the outside of the door—such as might break or displace an escapement-wheel—its inner end will project inward, so as to hold the locking-dog in the locked position. In conjunction with this safety-pin or stop I also employ another safety device described below.

In the accompanying drawings, Figure 1 is an elevation of so much of a safe-door locking and bolting mechanism as is necessary to illustrate my invention. Fig. 2 is a section of the same on the line 2 2 of Fig. 1.

Referring to the letters upon the drawings, A indicates a lock-case, which may contain time-lock mechanism of any ordinary character, and which is applied to a door, so as to leave an intervening space between them, as indicated in Fig. 2.

B indicates the carrying-bar of the bolt-work, of ordinary construction.

C indicates a dog or obstruction operated by the time-lock mechanism, so as to be held in the path of the bolt-work to prevent its retraction, except at the proper time, when the

time mechanism will cause it to drop down out 50 of the way and permit the bolt-work to be retracted.

D indicates a pin which passes through the case and projects across the intervening space x, and impinges or nearly impinges at one end 55 against the inside of the wall of the door X, as illustrated in Fig. 2. This pin is placed in position below the dog, so that if it is driven in by a force applied against the outside of the safe-door it will project into the path of 60 the dog and prevent its being lowered to permit the retraction of the bolt-work. The pin D may be held in place by friction, or by a slight screw-thread, so that a blow or explosion on the outside of the safe sufficient to 65 dislodge the time-movements would dislodge it and drive it inward, so as to prevent the release of the bolt-work. In connection with this unlocking-pin to guard against the derangement and running down of the time-lock, 70 I also employ a pivoted spring-bar, E, or equivalent device, as illustrated in Fig. 1, which, when the lock-case is in position upon the door, is held up against the force of its spring F by means of a stud, G, or otherwise, 75 in such position that it is normally idle and forms no obstruction to the retraction of the bolt-work; but in case the lock, by an explosion of dynamite or the like, should be blown off or started out of its position, so as to be 80 ineffective for locking, the pivoted bar or stop would, by the force of its spring and gravity, drop, so as to bring its end in front of a bar or projection, H, attached to the carrying-bar of the bolt-work and prevent its retraction. The 85 stud G may be made very narrow, so that a slight jar will cause the arm to drop. I do not claim the idea of using such a spring-bar in connection with a lock-case to be, broadly, 90 new; but when such a device is used in conjunction with a pin-projection, as above described, very thorough protection against attacks upon time-locks by the use of dynamite or the like is afforded. Either one or the other or both of these safety devices acting together 95 simultaneously, according to the character of the disturbance created, will interpose automatically, and as a consequence of the explo-

sion, to guard the bolt-work. When there is only a slight jar, both the pin and the spring-arm operate to dog the bolt-works; but when the lock is entirely blown off the spring-arm 5 alone acts.

Having thus described my invention, what I claim to be new, and desire to secure by Letters Patent, is—

1. The combination, with a lock-case (which, 10 when mounted, stands out from the door or side of the safe or vault, so as to leave an intervening space between them) and the dog of a lock, of a pin or stop projecting from the case, and located so that one end will receive the force 15 of a blow, or of an explosion upon the outside of a door, and the other end, when the pin is driven inward, will prevent the movement of the dog for unlocking, substantially as set forth.
2. A safe or vault door provided with bolt-

work and a time-lock and its case and dog, 20 (the lock being applied so as to leave an intervening space between it and the door,) in combination with a pin, D, projecting from the case, and located, substantially as set forth, for preventing the unlocking of the door when 25 the time-lock is interfered with by any unusual jar, and a spring-bar, E, normally supported by the time-lock case, and adapted to prevent the unlocking of the door when the time-lock is disturbed or blown entirely off, 30 substantially as and in the manner specified.

In testimony whereof I have hereunto subscribed my name this 10th day of February, A. D. 1883.

HERBERT C. STOCKWELL.
